SYNTHETIC THREAD MANUFACTURING APPARATUS

Harry A. Kuljian, Merion, Pa.

Application February 28, 1951, Serial No. 213,146

18 Claims. (Cl. 34—153)

1

In the continuous process manufacture of thread from viscose, the freshly coagulated thread is first treated with various chemicals to complete its regeneration and to give it the desired finish and is then dried before being twisted and spooled.

In cases where the thread is processed while it moves over a relatively large number of separated, independent thread storing and advancing reels or cages, the drying of the thread does not present any problem and any source of heat will do. This is due to the fact that thread can be passed over any desired number of heated reels or it can be passed through a drying chamber long enough to insure drying.

When, however, the freshly coagulated thread is to be completely processed and dried while it moves relatively rapidly over a single, relatively small thread advancing reel, adequate drying of the saturated thread presents a difficult problem.

It is therefore the object of the present invention to produce improved drying means for adequately drying a saturated thread while such thread moves through a relatively short zone near the discharge end of a relatively small thread storing and advancing reel.

A further object is to produce improved drying means which can be readily incorporated in a thread storing and advancing reel without increasing its over-all dimensions and without interfering with the operation of the reel.

These and other objects are attained by my invention as set forth in the following specification and as shown in the accompanying drawings in which

Fig. 1 is a fragmentary view, partly in side elevation and partly in section, of a thread storing and advancing reel provided with a drier embodying my invention.

Fig. 2 is a section taken on line 2—2 on Fig. 1.

Fig. 3 is an elevational view of the right hand end of the reel as viewed in Fig. 1.

Fig. 4 is a fragmentary top plan view showing details of construction.

Fig. 5 is a fragmentary and elevational view showing a slightly modified construction.

Fig. 6 is a section on line 6—6 on Fig. 5.

As will be seen from Fig. 1, the thread 10 to be processed is wound about the receiving end of a thread storing and advancing reel formed of a number of rolls, such as hollow rolls R1 to R8 arranged in a circle about a center post 11. The center post is carried by a suitable support 12 which also carries an inner end housing 13 in which is enclosed an inner end plate 14. The

shafts 16 which carry rolls R1 to R8 are provided, near their opposite ends, with self aligning bearings 15, and their opposite ends are carried by an inner end plate 14 and by an outer end plate 17 which will be hereinafter referred to. The rolls R1 to R8 are rotated about their axes by means of a gear 19 which is driven by a motor M and which meshes with gears 18 on the ends of the rolls. The reel parts so far described form no part of the present invention and are therefore not shown nor described in detail. It is sufficient to say that, when the outer end plate 17, in which the outer ends of the rolls are journaled, is rotated relative to the fixed end plate 14, the axes of the rolls will be skewed relative to the path of approach of the thread so that, when the rolls are rotated about their axes, the thread 10 will move, in the form of a helix circumscribing all of the rolls, from the receiving or left hand end, toward the right hand, or discharge, end of the reel.

As the thread 10 moves longitudinally of the reel, it is subjected to the action of regenerating and/or finishing liquids which are delivered to spaced zones along the reel through spaced, controlled nozzles N. The treatment of the thread with liquids also does not form part of the present invention and is therefore not shown nor described in detail. It is sufficient to point out that the liquid treatments stop at a point spaced from the right hand, or discharge end, of the reel to leave a zone Z in which the thread may be dried.

The center post 11 is made hollow and is provided with longitudinal slots 20 which are spaced to correspond to rolls R1 to R8 and which are substantially coextensive with the drying zone. Within the post 11 there is provided a steam inlet pipe 22, connected, by means of a pipe P1, to a source of steam, not shown, and a return pipe 24 for delivering the exhausted steam or the condensate, through pipe P2, back to a boiler or to a point of disposal, also not shown. The left hand end of the post is connected, by means of a duct D, to a source of compressed air having a constant temperature and a constant humidity. Surrounding that portion of post 11 which extends into the drying zone Z is a heat exchanger formed of a number of tubes 26 having heat exchange fins 28 for heating the air blown thereagainst through slots 20.

The finned tubes 26 are heated by steam, under pressure, delivered from pipe 22 into a passage 36 formed in header 38 and communicating with pipes 40 located within tubes 26, as shown in Figs 1 and 2. The open ends of pipes 40 are located

relatively close to the adjacent ends of tubes 26 so as to force the steam delivered through pipes 40 to flow in the opposite direction and thus produce a more even distribution of heat. The outer ends of tubes 26 communicate with a return passage 42 which leads, through passage 44, to return pipe 24 for removing exhausted steam, or condensate, from tubes 26.

In order to control the flow of the drying air, I provide horizontal baffles 46 which are secured at their outer ends to the header 38 and at their inner ends to a vertical baffle 48 by means of screws 50. The baffles 46 taper from their outer towards their inner ends so as to produce an oppositely tapered opening or space 52. By this arrangement, the air which is confined between header 38 and baffle 48 will flow out through openings 52 and because left hand ends of openings 52 are larger than their right hand ends, the volume of heated air will progressively decrease from left to right. Therefore, a large volume of heated air will flow against the saturated filament as it enters the drying zone Z and a progressively smaller volume of air will flow against the filament as it progressively dries while moving toward the discharge end of the reel.

In order to insure uniform performance, the humidity, volume, velocity, and temperature of the air delivered to the interior of center post 11 are kept constant so that the drying potential of the air, will be a function of the heat input. It will be noted that the heated air blows against the adjacent portions of the rolls as well as against the filament convolutions as they traverse the arcs subtended by the baffles 46. A thread passing through the drying zone will thus be dried by contact with the heated rolls and by the action of the heated air blown thereagainst.

In practice, I have achieved satisfactory drying of textile fabrics on a reel about 28" long and about 16" in diameter with the drying zone Z about 8" long. When heavy thread such as tire cord is to be dried, the effective length of the drying zone will be increased accordingly.

In the embodiment of Fig. 1, the headers 33 are secured to center post 11 by bolt 54 and end plate 17 is secured to header 38 by bolts 56. To skew, or to adjust the skew of, the rolls R1 to R8, the hold 54, alone, is loosened whereupon the end plate 17, the header 38, the baffles 46, and the baffle 48 are all rotated as a unit in the desired direction. After the desired skewing of the rolls has been effected, bolt 54 is again tightened. In order to secure positive joint movement of parts 38, 26, 46 and 48, with end plate 17 and thus maintain the relationships of these parts to each other and to the reel constant, one or more tie rods 58 are used to integrate these parts. The tie rods have their ends journaled in end plates 14 and 17 and pass through baffle 48, as clearly shown in Fig. 1.

In the embodiment of Figs. 5 and 6, the header 38 is secured to center post 11 by bolt 60, and end plate 17 secured to header 38 by bolts 62 which pass through arcuate slots 64 provided in end plate 17. To skew the rolls in this embodiment, bolts 62, alone, are loosened and end plate 17, alone, is rotated relative to header 38, center post 11 and end plate 14. Because, in this embodiment, the header 38, tubes 26, baffles 46 and baffle 48, do not move with end plate 17, the tie rods 58 are disposed with.

What I claim is:

1. For use with a thread advancing and storing reel including spaced, axially aligned first and

second end plates, an elongated post extending between said end plate, and a plurality of spaced elongated rolls arranged about said post and having their ends journaled in said end plates, a heat exchanger carried by said center post near said second end plate, means rotatably mounting said heat exchanger and said second end plate in relation to said post, and means for supplying a heated, fluid drying medium to said heat exchanger.

2. The structure recited in claim 1 in which said heat exchanger and said second end plate are independently rotatable relative to said post.

3. The structure recited in claim 1 said second end plate is rotatable relative to said heat exchanger and said post.

4. The structure recited in claim 1 in which said heat exchanger includes a header, inlet means for delivering a fluid drying medium to said heat exchanger through said header, and outlet means for removing the spent drying medium from said header.

5. The structure recited in claim 4 in which the center post is hollow and in which the inlet and outlet means are in the nature of pipes disposed within said post and communicating with said heat exchanger through said header.

6. The structure recited in claim 1 in which the center post is hollow and is adapted to receive air of a predetermined temperature, humidity and pressure and is provided with openings through which said air flows against said heat exchanger.

7. The structure recited in claim 1 in which the exchanger is in the nature of a number of elongated tubes positioned between and inwardly of said rolls.

8. The structure recited in claim 1 and a baffle substantially parallel to said second end plate and located adjacent the inner end of said heat exchanger.

9. The structure recited in claim 8 and elongated baffles located between, and inwardly of the outer peripheries of the rolls, and extending between said baffle and said second end plate.

10. The structure recited in claim 9 in which said elongated baffles taper longitudinally with the wide ends thereof near said second end plate and with the narrow ends thereof near said baffle.

11. For use in a thread storing and advancing reel including a first end plate, and a second end plate, a plurality of rolls disposed between, and having their opposite ends journaled in said end plates, a header located adjacent said first end plate and having a first passage and a second passage formed therein, elongated heat exchange tubes disposed inwardly of said rolls and communicating with said first passage, the other ends of said tubes being closed, a return pipe leading from said first passage, pipes leading from said second passage into said tubes, and an inlet pipe for delivering a fluid, heated, drying medium to said second passage.

12. The structure recited in claim 11, together with means rotatably mounting said first end plate and means securing said first end plate to said header.

13. The structure recited in claim 11 and a baffle spaced inwardly from said header and disposed inwardly of, and transversely of the axes of said rolls for confining the heat of said exchange tubes to space between said header and said baffle.

14. The structure recited in claim 13 and elongated

gated baffles disposed between, and inwardly of the outer peripheries of the rolls, said baffles extending longitudinally of said rolls.

15. The structure recited in claim 4 in which said elongated baffles taper in the direction of the axes of the rolls with the wide ends of said baffles in the vicinity of said header.

16. The structure recited in claim 11 and means for delivering air of a predetermined temperature and humidity to the exterior of said 10 heat exchange tubes.

17. A thread storing and advancing reel including a first end plate, a second end plate, a hollow center post extending between said end plates, a plurality of spaced, elongated rolls arranged in a circle about said center post with their opposite ends journalled in said end plates, a header adjacent said first end plate, heat exchange tubes communicating with said header and located between said center post and said rolls, means for delivering a heated fluid medium to the interior of said tubes, there being openings in said center post corresponding to said tubes for discharging air delivered into said center post radially against said heat exchange tubes. 15

18. A thread advancing reel including spaced,

axially aligned end plates, a center post extending between said end plates, a plurality of elongated rolls extending longitudinally of, and arranged around, said center post with the opposite ends of said rolls journalled in said end plates, a header mounted on said center post adjacent one of said end plates, means rotatably mounting said one end plate on said center post, means securing said end plate to said header, a first pipe extending longitudinally of said center post and communicating with said header for delivering a heated fluid medium to said header, a heat exchanger communicating with said header, and a second pipe extending longitudinally of said center post and communicating with said header for removing the exhausted fluid medium.
